CRACKING OF REDUCED CRUDE WITH CATALYST AND INERT PARTICLES

Edward W. S. Nicholson, Baton Rouge, La., assignor to
Esso Research and Engineering Company, a corporation of Delaware

Application May 10, 1951, Serial No. 225,550

2 Claims. (Cl. 196—52)

The present invention relates to a process of treating hydrocarbons. More particularly, the invention pertains to a method of producing from relatively heavy or high-boiling hydrocarbon oils of the type of topped or reduced crude or similar heavy residues increased quantities of motor fuel range fractions of improved quality as well as higher boiling distillate fractions suitable for further cracking. Broadly, the invention involves the catalytic cracking of heavy residues of the type mentioned above wherein the feed is contacted with fluidized catalytically inert solids and cracking catalyst.

In conventional petroleum refining, the crude petroleum is first distilled to produce various distillate fractions and a residue boiling above about 700° F. Motor fuels are normally produced from the distillate fractions by suitable refining processes including thermal or catalytic cracking, reforming, isomerization, alkylation, etc., while the residue is worked up to yield marketable high-molecular weight products, such as lubricating oils, waxes, asphalt, fuel oils, etc. More recently, however, the demand for motor fuels has increased so greatly that it has become desirable to use the residues from the crude distillation extensively as an additional source of raw materials for motor fuels.

It has been known for a long time that motor fuels may be produced by coking crude residua, that is by subjecting the residues to cracking at severe conditions including relatively high temperatures and long holding times. The use of cracking catalysts in this reaction has likewise been proposed. However, serious difficulties have been encountered in this type of operation chiefly as the result of the high ash content of the feed and the high rate of coke formation. Aside from the fact that the heavy coke deposits in the coking vessels and transfer lines require frequent cleaning periods and plant shut-downs, catalyst contamination and deactivation by coke and difficultly removable ash constituents of the feed is so rapid that crude residua have been considered highly undesirable as feed stocks for conventional catalytic cracking processes.

Some of these difficulties may be avoided in accordance with prior suggestions by coking residues in a dense turbulent bed of hot subdivided catalytically inert solids, such as coke, pumice, kieselguhr, spent clay, or the like fluidized by upwardly flowing gases or vapors. These solids serve primarily as a carrier for the coke formed and as a scouring agent preventing coke deposition on equipment walls. Also gasoline yields are somewhat higher as a result of the high surface area of the solids. The coke deposited on the solids may be burnt off in a separate fluid-type heater vessel from which hot solids may be returned to supply heat required for cooking. It is a matter of record that fluid operation affords greatest advantages with respect to heat transfer and economy, temperature control, ease and continuity of operation, etc.

While procedures of this type avoid catalyst contamination and heat supply by circulating catalyst, they are essentially thermal rather than catalytic in character and, therefore, result in the production of motor fuels of rela-

2

tively low octane rating. The addition of a cracking catalyst in itself to the inert material is no complete solution of the problem because there still remains the difficulty of catalyst contamination and deactivation by ash constituents of the feed, which cannot readily be removed by simple oxidative regeneration. The present invention overcomes these difficulties.

It is, therefore, the principal object of the invention to provide improved means for producing motor fuels by coking heavy residua in contact with fluidized inert solids and cracking catalysts. Other objects and advantages will appear from the description of the invention given below wherein reference will be made to the accompanying drawing.

In accordance with the present invention, heavy residues of the type specified above are coked by passing the feed at coking conditions upwardly through a fluidized mass consisting of relatively coarse inert solids and of relatively fine cracking catalyst in such a manner that substantial upward elutriation of relatively fine catalyst from relatively coarse inert solids takes place with the effect that the feed is maintained at cracking conditions in contact with a mixture of a catalytically inert mass of solids and cracking catalyst. Fresh active cracking catalyst of relatively small particle size is continuously supplied to this bed and removed therefrom by elutriation substantially at the same rate at which it is contaminated. In this manner, the solids mixture is continuously maintained at a desirable level of catalytic activity and selectivity to valuable volatile conversion products. In addition to being of smaller particles size, the catalyst may be of lower density to permit or enhance this type of operation. It has also been observed that the relative entrainment rate of the smaller or lighter particles is substantially increased when coke is preferentially deposited thereon. This takes place in the case of the present invention because of the higher cracking activity of the catalyst particles as compared with that of the inert material.

The preferred embodiment of the invention provides for a single-pass operation with respect to the catalyst. The oil stream containing the relatively small sized and/or low density catalyst may be preheated in a conventional coil furnace and then superheated to cracking temperatures by addition of relatively coarse and/or dense inert solids circulated from a burner vessel. The catalyst may also be added subsequent to the addition of inert solids. When the mixed feed enters the reactor, catalytic cracking takes place in the fluidized state and the more entrainable catalyst passes overhead with the product oil vapors and may be separated from the product oil in gas-solids separators, slurry settlers and/or other conventional means, to be withdrawn from the system. Elutriation of catalyst from the dense fluidized phase may be enhanced by providing a perforated grid or packing above the dense phase or raising the dense phase level so as to reduce the volume of the disperse phase within the reactor to a minimum. The less entrainable inert solids may be downwardly withdrawn from the dense phase and circulated to a burning vessel to be reheated therein and to be returned to the reactor for heat supply. This operation eliminates the recycle of catalyst contaminated with feed contaminants which would cause poor product distribution. The catalyst containing such contaminants is continuously discarded, preferably after passage through the burner vessel, and essentially all the cracking takes place in contact with fresh relatively uncontaminated catalyst.

Fluidization conditions may be maintained within conventional ranges. The relative particle sizes of the catalyst and inert solids depend, of course, to a certain extent on their relative densities. Assuming substantially equal densities of the order of that of coke and conventional natural or synthetic clay catalysts, the inert solids may have

a particle size of about 100-500 microns and the catalyst a particle size of about 80 microns and less. Linear superficial velocities of the fluidizing medium in the cracking zone may vary from about 0.5-10 ft. per sec. to establish apparent densities in the dense mixed solids phase of about 10-50 lbs. per cu. ft. and about 0.001-1 lb. per cu. ft. in the disperse phase.

Reaction conditions may include oil preheating temperatures of about 300°-900° F., coking and cracking temperatures of about 800°-1200° F., and inert solids regeneration temperatures of about 1050°-1500° F. or higher. In the cracking operation, the ratio of total solids to oil may be from about 1:1 to about 20:1 by weight. The proportion of inert material to catalyst may be from about 5:1 to about 1000:1 by weight.

While some of the inert solids previously suggested for the coking of residues in fluid operation such as sand, pumice, spent clays, silica gel, etc. may be used, coke affords greatest advantages in the process of the invention because product coke deposited on this material forms a valuable by-product which may be recovered as a high B. t. u. fuel, as a raw material for activated carbon, and for other purposes. Extraneous coke from petroleum or coal may be used to start up the process while thereafter product coke may serve as the inert solid. The product coke may be withdrawn and at least part of it ground to provide fresh seed coke. An alternative method for continuously providing seed coke without withdrawing product coke from the unit is the inclusion of a supersonic attriter in the coke cycle as it is known in the art of fluid catalytic cracking. While conventional cracking catalyst including activated clays, activated alumina, synthetic composites of silica with alumina, magnesia and/or boria, etc., may be used, inexpensive expendable catalysts of moderate activity such as activated carbon, Attapulgus clay, etc. are preferred.

Having set forth its objects and general nature, the invention will be best understood from the more specific description hereinafter read with reference to the drawing, the single figure of which is a semi-diagrammatical illustration of a system suitable to carry out a preferred embodiment of the invention.

Referring now in detail to the drawing, a crude residuum such as an 8% bottoms fraction from the vacuum distillation of a West Texas crude or a similar heavy residue may be admixed in line 3 with about 5-50 lbs./bbl. of an expendable catalyst such as activated carbon or Attapulgus clay supplied through line 5. The catalyst may have a particle size of up to about 80 microns. The catalyst-oil mixture may be preheated in a conventional coil furnace indicated at 7, to temperatures of about 600°-900° F. The preheated feed may then be admixed in line 8 with hot inert solids having a particle size of about 100-500 microns supplied from a conventional standpipe 9 provided with aeration and/or stripping taps *t*, the solids being at a temperature of about 1000°-1500° F. and in amounts of about 700-3,000 lbs./bbl. The mixture in line 8 may have a temperature of about 800°-1200° F. conducive to cracking and complete vaporization of the oil. The solids-in-gas suspension formed may enter reactor 10 through a distributing grid 12. Feed rates and reactor design are so chosen that a dense, turbulent, fluidized mass of solids *M*₁₀ having an interface *L*₁₀ and an apparent density of about 20-50 lbs. per cu. ft. is formed which provides for an additional vapor contact time of about 2-10 seconds, catalyst being selectively entrained in the product vapors and carried overhead to form a disperse phase *D*₁₀ having an apparent density of about 0.002-0.1 lbs. per cu. ft. in which cracking is completed. Linear superficial vapor velocities in reactor 10 of about 2-10 ft. per sec. are normally suitable for these purposes. This entrained catalyst will carry the bulk of the coke produced by cracking in vessel 10 because it is continuously supplied in a fresh highly active state. Product vapors and entrained catalyst are with-

drawn through cyclone 14 and thence through line 16 to conventional product recovery equipment, if desired after further separation of entrained catalyst in any suitable manner known per se. Catalyst separated in cyclone 14 may either be returned via line 18 to mass *M*₁₀ for control of hold up and/or apparent density or discarded through line 20, and/or passed through line 21 to reheater 26 to generate heat therein as will appear hereinafter.

Fluidized solids consisting predominantly of coarse inert solids concentrating in the lower portion of reactor 10 and containing by far the largest proportion of the non-catalytic coke, i. e. the coke formed from the non-vaporizable asphaltene constituents of the feed by vaporization and thermal cracking may be withdrawn through conventional standpipe 22 and supplied to line 24 substantially at the rate of solids flow through line 9. The inert solids are picked up in line 24 by air and carried in dilute suspension to a lower portion of reheater 26 through a distributing grid 28. The air feed rate to reheater 26 may be so controlled that the inert solids are reheated therein by combustion of coke to about 1000°-1500° F. in dense phase fluid operation at superficial linear gas velocities of about 1-10 ft. per sec. Flue gases containing entrained solids may be withdrawn through separator 30 and line 32, separated solids being returned through line 34 or discarded via line 36. Make-up inert solids may be supplied through line 38. Hot inert solids may be supplied via standpipe 9 to line 8 as described above. If the carbon deposited on the inert solids in reactor 10 is insufficient to maintain by combustion the desired temperature in reheater 26, a torch oil or fuel gas may be injected to the reheater through line 40. Preferably, additional heat is generated by supply of coked catalyst through line 21 as described above. Catalyst particles subjected to combustion in reheater 26 may be removed therefrom by entrainment in the flue gases and discarded.

If desired, a horizontal grid plate similar to plate 12 but having a higher percentage of open area may be arranged in the upper portion of reactor 10 to promote the formation of a second fluidized bed in reactor 10 above bed *M*₁₀ on top of the second grid plate, thus to enhance the utilization of the catalyst before it is discarded. Rather than supplying the fresh catalyst mixed with the oil feed to line 3, the fresh catalyst may be added through line 42 after the addition of the inert solids.

Catalyst removal from the system by entrainment from mass *M*₁₀ has been above referred to. It should be understood, however, that catalyst removal may also be accomplished by passing substantially all the catalyst contained in mass *M*₁₀ together with inert solids through lines 22 and 24 to reheater 26 from which the catalyst may be removed by entrainment substantially as described above. For this purpose, it is sufficient to run reactor 10 at relatively low fluidizing velocities of, say, 0.5-3 ft. per sec. and reheater 26 at relatively high velocities conducive to catalyst elutriation.

While in the above examples reference has been made to the use of catalyst in a form more readily entrainable than the inert solids and this is the preferred embodiment of the invention, it is noted that some of the advantages of the invention may be secured when the inert solids are used in a more readily entrainable form than the catalyst. If desired, the systems illustrated may be readily adapted to this type of operation in a manner obvious to those skilled in the art.

The foregoing description and exemplary operations have served to illustrate specific embodiments of the invention but are not intended to be limiting in scope.

What is claimed is:

1. The process of converting heavy residual hydrocarbon oil to more volatile products and coke, which comprises feeding said oil in preheated condition into contact with (a) a small proportion, between about 5 and 75 50 pounds per barrel of feed, of finely divided preheated

expendable solid catalyst and (b) at least 5 times as large a proportion, compared to the weight of catalyst, of relatively coarse, preheated, catalytically inert solid particles from which the finely divided catalyst can be readily elutriated, passing a gasiform fluid upwardly through a mass of said catalyst and inert solids in a contacting zone so as to maintain said mass in fluidized condition and at such velocity as to substantially completely elutriate the catalyst therefrom after a contact time of about 2 to 10 seconds between oil and catalyst in the contacting zone, and thereafter withdrawing, re-heating and recycling to the reaction zone at least a portion of the inert solids, substantially free of catalyst to maintain a cracking and coking temperature between 800 and 1200° F. in said zone.
